(57) **CLAIM**

The ornamental design for a gas diffuser as shown and described.

DESCRIPTION

FIG. 1 is a top front right side view of a gas diffuser according to our design.

FIG. 2 is a bottom front right side view thereof.

FIG. 3 is a top rear left side view thereof.

FIG. 4 is a bottom rear left side view thereof.

FIG. 5 is a front view thereof.

FIG. 6 is a rear view thereof.

FIG. 7 is a right side view thereof.

FIG. 8 is a left side view thereof.

FIG. 9 is a top plan view thereof.

FIG. 10 is a bottom plan view thereof.

FIG. 11 is an enlarged top side isometric view taken from FIG. 3.

FIG. 12 is an enlarged bottom side isometric view taken from FIG. 4; and,

FIG. 13 is a cross-sectional view taken along the section line 13 in FIG. 9.

(Continued)

The dashed lines shown in the figures depict portions of the gas diffuser that form no part of the claimed design.
